WRINGER

Gustave H. Jantz, Cincinnati, Ohio, assignor to Lovell Manufacturing Company, Erie, Pa., a corporation of Pennsylvania

Application October 25, 1934, Serial No. 749,977

51 Claims. (Cl. 68—263)

1

My invention relates to wringers employable for wringing clothes, and is of that class of wringers having wringer rolls between which the goods are passed and pressed for expressing the liquid therefrom.

It is the object of my invention to provide novel means for resisting pressure between the wringer rolls, further, to provide novel means for a pressure between the wringer rolls that may be quickly and effectively relieved for avoiding accidents; further, to provide novel means for operating the relieving mechanism; and, further, to provide novel means for maintaining the parts of the relieving mechanism in relieved relation.

The invention consists in novel means for attaining these objects; further, in providing a novel linkage mechanism for drawing the resistance means resisting pressure between the wringer rolls into operative relation; further, to provide novel means for holding such mechanism in operative relation, and, further, to provide novel means for relieving such operative relation to permit quick separation between the wringer rolls.

My invention consists, further, in the novel parts and in the novel construction, arrangements and combinations of parts herein shown and described.

In the drawings:

Fig. 1 is a front elevation of my improved device.

Fig. 2 is an end elevation of my improved device, viewed from one end of the same, and partly broken away.

Fig. 3 is an end elevation of the same, viewed from the opposite end of the device.

Fig. 4 is a vertical cross-section showing a portion of the relieving means, taken on the line 4—4 of Fig. 1.

Fig. 5 is a horizontal section of the same, taken in the plane of the line 5—5 of Fig. 4.

Fig. 6 is a perspective view of the cross-bar of the relieving mechanism.

Fig. 7 is a central vertical longitudinal section of my improved device, showing the parts in operative relation.

Fig. 8 is a similar view of the same, showing the parts in relieved relation; and,

Fig. 9 is a vertical section of a detail of the relieving means, taken in the plane of the line 9—9 of Fig. 8.

I have exemplified my improved device as applied to a wringer of the character of that shown, described and claimed in my Letters Patent of the United States No. 1,932,288, for Wringer, dated October 24, 1933, and the general structure and purpose of the relieving bar of general inverted U-form such as herein shown and described is disclosed in my Letters Patent of the United States on improvements in

2

Wringers, No. 1,408,807, dated March 7, 1922, and No. 1,810,479, dated June 16, 1931.

In the present exemplification there is a rigid frame 11 which comprises a longitudinally extending base 12, from the respective ends of which posts 13, 14 extend upwardly. The frame is shown made of sheet metal bent into channel form. The respective sides of the frame are provided with downwardly sloping shelves 15, having upwardly extending end flanges 16 curvingly bent therefrom.

Clothes guards 18 are located at the inner faces of the upright posts, the clothes guards and such inner faces and the inner walls of the upright posts being provided with upright slots 19.

Wringers 21, 22 are provided with shafts 23, 24. Lower bearings 25 and upper bearings 26 are located in the channels of the upright posts, the shafts of the wringer rolls being journaled in these bearings. One of the shafts may have one end extended through a slot 27 in the outer wall of one of the posts and be provided with suitable means, exemplified at 28, for attachment of a driving means.

A longitudinal bar 31 resists pressure between the wringer rolls. It is shown as a top bar extending between the upper ends of the posts, and is shown provided with an upper wall 32, depending side walls 33 and depending end walls 34, 35, forming a downwardly opening hollow 36 in the top bar. The upper ends of the posts are received in the ends of this hollow in the top bar, the top bar being received canopywise over the upper ends of the posts.

This bar is movably secured to the frame, permitting pressure to be exerted upon the wringer rolls, and quick release means are provided permitting relief of such pressure when the top bar is released.

A bow spring 39 is shown located between the top bar and the wringer rolls, the respective ends of the bow spring extending through the slots 19 in the inner walls of the upright posts and resting upon the upper bearings 26 of the wringer rolls. It has a seat 40 in its middle portion, receiving the lower rounded end of a screw 41 having threaded connection 42 with a nut 43 secured to and extending through the top bar, the screw having a knob 44 at its upper end for rotating the same.

There is a releasable connection 48 between one end of the top bar and one of the posts, arranged to be released and connected by opposite endwise movements of the top bar. It is exemplified as comprising a knob 49 received in a hole 50, the knob being shown on the post and the hole in the end wall of the top bar. The hole is preferably elongated as a slot for readily receiving the knob.

A linkage mechanism 51 is provided for con-

60

necting the other end of the longitudinal bar and the frame, and is exemplified as a link 52 having pivot connection 53 with the end of the top bar and a link 54 having pivot connection 55 with a post adjacent to its upper end. These links extend from these pivot connections, and are interpivoted at their outer ends by a pivot 56. The link 52 is extended beyond the pivot 56 to form a lever. The outer end of the lever forms a handle 57.

This lever is preferably formed out of sheet metal, with an inwardly extending marginal flange 61, the pivots 53, 56 having bearings at their opposite ends in opposite portions of this flange.

The pivot 53 has bearing 62 in a bracket 63 fixed to the end wall 34 of the top bar, the bearing extending outwardly from this end wall. The pivot 55 has bearings in lugs 64 struck outwardly from the upper end of the post. The marginal flange of the lever forms a pocket in the inner face of the lever. The inner portions of the pivots 53, 56 and the bearings therefor, as well as the link 54 and the pivot 55 and its bearings, are received in the pocket of the lever when the lever is moved toward the frame in operative relation, to provide compactness of parts, to conceal the covered parts, and to provide a flush and pleasing appearance for the linkage connecting end of the wringer.

The pivot 56 forms a toggle between the links 52, 54, that is, between the operating lever and the link 54, so arranged that when the lever is moved toward operative position for placing the parts for pressure relation between the rolls, the pivot 56 is moved toward the plane, exemplified by the dot and dash line 65, in Fig. 7, in which the axes of the pivots 53 and 55 are located, for drawing the top bar or frame, which may be considered as a frame part, toward the main frame for connecting said parts for pressure between the wringer rolls. This places the pivot 56 proximate to said plane, but preferably at the outside thereof, so that there is preferably a tendency toward separation between said parts.

Movement of the pivot 56 toward the plane in which the pivots 53, 55 are located, moves the links 52, 54 from the acute angular relation exemplified in Fig. 8 into substantial parallelism, exemplified in Fig. 7, thereby drawing the connected parts toward each other into operative relation.

A latch 68 is provided for releasably holding the parts in such relation. The latch has a hook 69 received over a lug 70 fixed to the lever. It is provided with pivot lugs 71, forming bearings about a pivot pin 72, located in bearing holes 73 in the frame. The latch is provided with a cam part 74, shown extending inwardly therefrom to form a lever. A spring 75 is fixed to the frame and bears against the lever, as against the cam-formed tail thereof, for resiliently urging the latch into engaging relation. The lug 70 is provided with an inclined face 76, upon which the hook end of the latch rides into engagement with the lug 65 when the lever is moved toward the frame.

The means exemplified for releasing the latch comprise a cross-bar 80, provided with oppositely extending cam faces 82, 83 coacting with the cam part of the latch. The oppositely presented cam faces on the cross-bar and the contact part therefor on the latch may, of course, be reversed if desired. There is a further cross-bar 81. The cross-bars may each be a piece of sheet metal bent to have a top wall 84, depending side walls 85 and

end walls 86, the opposing cam faces being shown formed in one of the side walls.

Means are provided so that the cross-bar 80 may be operated from each side of the wringer by movement in either direction, and means are provided at each side of the wringer for effecting such movement. There is a releasing bar of general inverted U-form, such as exemplified in my aforesaid patents, Nos. 1,408,807 and 1,810,479, at each side of the wringer. Each of these releasing bars 87 comprises a top or hand rail 88 and depending sides 89, 90, arranged about the top and end of the wringer roll opening in the front and rear of the frame. The hand rails are parallel to each other. Each of the posts has at each side thereof a bearing bracket 91 fixed to the wall of the post, as by spot-welding, and preferably formed up out of sheet metal, and having a bearing 92 therein for the downwardly extending branch of the releasing bar. Each of these downwardly extending branches is proximate to this point provided with an inward bend 93 for projecting the upper ends of the releasing bars slantingly outward for placing them in positions to be readily grasped by the operatrix in case she desires to take quick action in separating the rolls. Any part of each of these releasing bars may be moved toward or from the wringer frame for such release.

30 The lower ends of the depending sides of these releasing bars are reduced in cross-section, as shown at 94, to form stems received in bearings 95 in the cross-bar 80, 81 and shoulders 96 to rest upon the cross-bars. Each of these depending sides has an enlargement 97, shown as a screw threaded into the bar under its bearing 92 for holding the bar downwardly.

Each of the brackets 91 is provided with an inwardly extending portion 98, extending through 40 a slot 99 in the respective front and rear walls of the posts, to form shelves on which the lower bearings of the wringer rolls rest.

The front and rear walls of the posts are also provided with holes 100 of cross-sectional form, similar to that of the cross-bars 80, 81, to form bearings in which these cross-bars slide endwise.

45 In order to hold the cam mechanism between the cross-bar and the latch normally in neutral relation, I provide the cross-bar 81 sliding endwise in its bearings. This cross-bar may be devoid of the oppositely presented cam faces 82, 83, if desired.

Oppositely acting springs 101, 102 are received about the cross-bar 81 inside the channel of the frame between the front and rear walls of the frame. A pin 103 is in the middle portion of the cross-bar 81 between the springs. This pin may be a cotter-pin received through a hole 104 in the middle of the cross-bar, and positions the inner ends of the springs. When one of the releasing levers is moved in one direction, one of the springs is compressed, and when either of the releasing levers is moved in the opposite direction, the other of the springs is compressed, the springs returning the operating levers to normal positions and returning the cam-actuating means for the latch into normal relation upon release of the operating levers.

70 A keeper 105 shown formed in the top of the post 13 receives the end wall 34 of the top bar and holds the top bar from automatically returning about the post 13 and prevents automatic reengagement of the releasable connection 48, for keeping the parts in release relation.

75 In case of accident the operatrix may quickly

relieve pressure between the wringer rolls by contact with any portion of the top or depending sides of either releasing bar and either pushing or pulling the same toward or from the wringer frame, whereby the cross-bars 80, 81 are moved longitudinally, one of the cam faces of the bar 80 actuating the latch 68 for movement of the lever 57 in releasing direction, whereby the toggle links 52, 54 are moved into release relation, the parts in the present exemplification being moved from their relation shown in Fig. 7 to their relation shown in Fig. 8 by the pressure between the wringer rolls.

During this movement of the parts, the end wall 34 of the top bar is raised above the top of the post 13 and the top bar is moved longitudinally for releasing the releasable connection 48, for removing all pressure between the wringer rolls and permitting raising of the upper roll and the top bar and the parts therebetween for complete release of everything which may be between the rolls.

Upon descent of the raised end of the top bar the end wall 34 engages the keeper 105 and prevents automatic reengagement of the releasable connection 48 for holding the parts in release relation. Explaining the operation more in detail, and referring particularly to Figs. 7 and 8, it may be stated that upon sudden release of the pressure upon the spring 39 and consequent release of pressure between the wringer rolls due to release of the latch 68 in the present exemplification, a sudden upward movement is imparted to that portion of the top bar with which the spring connects, being the middle portion of the top bar in the present exemplification.

The right-hand end of the top bar as viewed in Fig. 7 is momentarily held to the main frame by the releasable connection 48, causing the motion of the top bar to be translated into an arcuate motion about the releasable connection 48 as a center, for swinging the left hand end of the top bar upwardly and endwise toward the right, carrying the pivot 63 with it, for opening the hinge formed by the links 52, 54, and swinging the pivot 56 between the links outwardly and upwardly. The lower end of the lever 57 is simultaneously swung outwardly and upwardly. These movements in the present exemplifications are in the plane of the wringer frame.

The quick sudden upward forceful movement of the pivot 53 carries the lever 57 with it and swings the lever upwardly upon the pivot 53, qualified by the outward swinging movement of the link 54 about its pivot 55 on the main frame, and the pivot connection 56 between the swinging end of this link 54 and the lever.

This reacts upon the upper end of the link portion 52 of the lever, which is that portion of the lever above the pivot 56, as hereinbefore explained, and which is longer than the link 54, moving this upper end of the link portion 52 of the lever inwardly toward the vertical plane in which the post 13 is located, and above this post, thereby raising the end wall 34 of the top bar above this post and tilting the top bar upon its releasable connection 48, and automatically moving the top bar endwise to the right with relation to the posts, as viewed in Fig. 8, thereby moving the end wall 35 of the top bar and the wall of its hole 50 beyond the knob 49, whereby this end of the top bar is released.

This action or sequence of movements of the parts is extremely rapid, and it may be said almost instantaneous, the recoil of the spring 39

practically shooting the parts through the motions stated due to their connections. The upward and endwise movement of the top bar is limited by the links 52, 54 and their pivotal connections, preventing dangerous extent of movement of the top bar and its connected parts.

The releasable connection 48 holds the right hand end of the top bar to the post 14 during the initial portion of these movements, whereby forceful upward movement of the right hand end of the top bar is prevented, removing all danger from the movements of the parts, and during the balance of these movements the right hand end of the top bar rests upon the post 14.

The pivot 56 may during the release motion rise to the level of the pivot 55 or above said level, and if strong tension is applied to the spring 59, the pivot 56 will be raised sufficiently by the recoil of the resilient pressure of the rolls and spring upon release of the latch 68, to almost fully open the links 52, 54 with relation to each other, movement of the pivot 56 into a right line between the pivots 53, 55 when the links are in such almost fully open relation being prevented by having the free edge of the marginal flange 61 engage the upper edge of the outer end wall of the post 13.

The motive power for the separating movements is the energy stored in the resilient pressure between the wringer rolls and in the spring 39, released by release of the latch 68, in the present exemplification.

When the relieving movements of the parts have been completed, the raised parts drop by gravity, the top bar remaining in endwise moved relation, so that the bottom of the end wall 34 automatically becomes seated in the seat 105 as shown in Fig. 8, the effect of which is to prevent re-engagement of the releasable connection 48.

These movements are entirely automatic and quick upon release of the safety latch 68.

In this relation the top bar with its attached spring may be completely manually raised from the wringer rolls by swinging the top bar upwardly on its link connections with the main frame.

If it is desired to again place the parts in operative relation, the end of the top bar adjacent to the keeper 105 is raised and the top bar is moved longitudinally to place its end wall 34 at the outside of the post 13, thereby engaging the releasable connection 48. The handle 57 is then depressed for moving the toggle links 52, 54 into substantial parallelism, thereby exerting pressure upon the wringer rolls, the adjusting screw 42 being adjusted if desired.

When the handle 57 has substantially reached its limit of movement, engagement in the latch 68 automatically takes place, for holding the parts in operative relation, it being understood that the hook 69 will have been automatically returned to engaging position by the action of the springs 101, 102 returning the cross-bar 81 to normal position, which acts on both the releasing bars for returning them to normal positions. The latter act to return the cross-bar 80 to normal position, thereby permitting the hook 69 to return to normal or latching relation, urged thereto by the spring 75.

The cupped lever 57 covers the operative parts located between it and its adjacent post 13.

I claim:

1. In a wringer including a lower frame and a longitudinal bar, wringer rolls and pressure means therefor between said lower frame and said lon-

itudinal bar, said pressure means positioned to produce pressure between said wringer rolls, the combination of a releasable connection between one of the ends of said longitudinal bar and said lower frame, connecting means between the other end of said longitudinal bar and said lower frame comprising interpivoted links of different lengths pivoted to said longitudinal bar and to said lower frame and normally extending in the same general direction from said longitudinal bar and said lower frame, means whereby to move the pivot between said links in one direction for drawing said longitudinal bar toward said lower frame and to move said last-named pivot in the opposite direction for moving said longitudinal bar away from said lower frame and to release said releasable connection while all said pivotal connections are maintained, and a keeper between said longitudinal bar and said lower frame to hold said releasable connection in release relation.

2. In a wringer having a frame comprising end posts, a top bar, wringer rolls and pressure means therefor operatively disposed between said frame and said top bar, said pressure means positioned to exert pressure upon said wringer rolls, the combination of a releasable connection between one end of said top bar and one of said posts, and connecting means between the other end of said top bar and the other of said posts comprising interpivoted links pivoted respectively to said other end of said top bar and to said other of said posts and arranged to be moved into substantial parallelism for effecting wringing pressure between said rolls and out of parallelism, while maintaining all of said pivotal connections, for enabling relief of said pressure, and for movement of said top bar for release of said releasable connection.

3. In a wringer having a frame comprising end posts having wringer rolls journaled therein, a top bar, said frame and said top bar forming a pair of frame members, pressure means operatively disposed between one of said frame members and said wringer rolls for exerting pressure upon said wringer rolls, the combination of a releasable connection between one end of said top bar and one of said posts, connecting means between the other end of said top bar and the other of said posts comprising interpivoted links pivoted respectively to said other end of said top bar and to said other of said posts and arranged to be moved into substantial parallelism for effecting pressure between said rolls and out of parallelism for enabling relief of said pressure, such movement out of parallelism raising said other end of said top bar about said releasable connection as a center and moving said top bar endwise for release of said releasable connection, and a keeper acting on said top bar resisting return endwise movement of said top bar for maintaining release of said releasable connection.

4. In a wringer, the combination of opposed wringer parts for receiving wringer rolls therebetween, mechanism including a toggle between said parts for producing wringing pressure between said rolls, said toggle comprising a longer link continuously pivoted to one of said parts and a shorter link continuously pivoted to the other of said parts, a latch for said toggle, and releasing means for said latch.

5. In a wringer having a frame, wringer rolls journaled therein, a longitudinal bar and pressure means; the combination of connecting means between said frame and said longitudinal bar resisting pressure between said wringer rolls, pressure relieving means for said connecting means

10 comprising a movable cross-bar having oppositely presented slanting cam surfaces cooperating with said connecting means, and operating levers having portions at the top and ends of the wringer rolls, said levers pivoted to said frame for movements toward and from said frame at the respective sides of said wringer and having connections with said cross-bar for moving said cross-bar by each of opposite movements of said operating levers.

6. In a wringer having a frame comprising opposed frame sections, wringer rolls between said frame sections, and pressure means; the combination of connecting means between said frame sections resisting pressure between said wringer rolls and including a latch, a release bar at each side of said frame, a movable cross-bar at each end of said frame having connections with said release bars for being moved thereby, one of said cross-bars having oppositely presented cam surfaces cooperating with said latch, and oppositely acting spring means having operative connection with the other of said cross-bars for normally holding said cam surfaces in neutral relation.

7. In a wringer having a frame comprising end posts and a top bar, bearings in said posts including lower bearings, and wringer rolls journaled in said bearings, the combination of connecting means between said top bar and said end posts comprising a latch, and releasing means for said latch comprising a bar at each side of said frame, a bracket fixed at each side of each of said posts and having a shelf extending into the inside of the post, said shelves forming supports for said lower bearings, a movable cross-bar in each of said posts having connections with said respective bars for moving said cross-bars, one of said cross-bars having oppositely presented cam surfaces co-operating with said latch for releasing said latch

25 by opposite movements of said bars, and oppositely acting spring means operatively connected with the other of said cross-bars for normally holding said cam surfaces cooperating in neutral relation.

8. In a wringer having opposed wringer members, wringer rolls therebetween, and pressure means between said members and said wringer rolls to produce pressure between said wringer rolls; the combination of interpivoted links pivoted to said respective members, means whereby to move the pivot between said links toward the plane in which the pivots between said links and said members are located, and safety release means acting to hold said links in such moved relation and to release said links for movement of said pivot between said links in opposite direction, said links having maintained articulations by said pivots with each other and with said members for limiting separation between said members.

9. In a wringer having opposed wringer members, wringer rolls therebetween, and pressure means between said members and said wringer rolls to produce pressure between said wringer rolls, the combination of interpivoted links pivoted to said respective members, means whereby to move the pivot between said links toward the plane in which the pivots between said links and said members are located, and a safety release acting to hold said links in such moved relation and including a lever having upper and end stretches about the normal positions of said wringer rolls and having operative connection with said links which when released permits movement of said pivot between said links away from said plane, said links having maintained articulations by said pivots with each other and

70 75

with said members for limiting separation between said members.

10. In a wringer having opposed wringer members, one of which is movable lengthwise with relation to the other, wringer rolls therebetween, and pressure means between said members and said wringer rolls to produce pressure between said wringer rolls, the combination of releasable connecting means between said members at one end of the same, interpivoted links pivoted to the other end of said members, means wherewith to move the pivot between said links toward the plane in which the pivots between said links and said members are located to produce pressure between said wringer rolls, and safety release means acting to hold said links in such moved relation, said pressure means and said safety release means acting on said links to effect movement of said pivot between said links away from said plane.

11. In a wringer having opposed wringer members, one of which is movable lengthwise with relation to the other, the wringer rolls therebetween, the combination of releasable connecting means between said members at one of their ends, interpivoted links pivoted to the other end of said members, means wherewith to move the pivot between said links toward the plane in which the pivots between said links and said members are located, and pressure means between said members and said wringer rolls to produce pressure between said wringer rolls, and safety release means acting to hold said links in such moved relation and to release the links for movement of said pivot between said links in opposite direction away from the plane of the pivots with an upward swinging movement, whereby said lengthwise movable member is urged tiltingly lengthwise to release said connecting means, and said links having maintained articulations by means of said pivots with each other and with said members for limiting separation between said other end of said members.

12. In a wringer having opposed wringer members, one of which is movable lengthwise with relation to the other, wringer rolls therebetween, and pressure means between said members and said wringer rolls to produce pressure between said wringer rolls, the combination of releasable connecting means between said members at one of their ends, interpivoted links comprising a longer link pivoted to the other end of said one member and a shorter link pivoted to the other end of the other of said members, means wherewith to move the pivot between said links toward the plane in which the pivots between said links and said members are located, and safety release means to hold said links in such moved relation, said pressure means and said safety release means acting together on said links for movement of said pivot between said links in opposite direction to urge said lengthwise movable member lengthwise to release said releasable connecting means, said links having maintained articulations by means of said pivots with each other and with said members for limiting separation between said members.

13. In a wringer having lower and upper wringer members, wringer rolls therebetween, and resilient means to exert pressure on said rolls and urge separating movement between said wringer members, the combination of means to develop wringing pressure in said resilient means comprising an outwardly endwise opening releasable connection between one of the ends of said

wringer members and interpivoted links pivoted to the other end of said respective wringer members and normally extending in the same general direction therefrom in the plane of said wringer rolls when said wringer members are in connected pressure relation, latching means for said links, and safety release means for said latching means, all whereby to automatically move said other end of said upper wringer member upwardly in an arc and endwise to open said links and release said releasable connection.

14. In a wringer having a lower member, an upper member, wringer rolls between said members, and pressure means for exerting pressure on said wringer rolls, the combination of interpivoted links pivoted to one end of said members, outwardly endwise releasable connecting means between the other end of said members, one of said links being longer than the other at one side of its interpivoting pivot and extended as a lever at the other side of its interpivoting pivot wherewith to move the interpivoted ends of said links toward the plane in which the pivots between said links and said respective members are located for building up pressure in said pressure means, means whereby to hold said links in such moved relation, and safety release means having operative connection with said holding means for movement of said interpivoting pivot away from said plane, for release of said pressure and endwise movement of said upper member for release of said connecting means.

15. In a wringer having a frame having feeding openings for access to the wringer rolls at the respective sides thereof, pressure applying means for said wringer rolls, the combination of a transverse bar transverse to the frame and movable in opposite directions in the frame, release levers at the respective sides of said frame having fulcrums on said frame and extending along the top and ends of said respective feeding openings and articulated with said transverse bar for operating the same, and double acting cam means having slanting cam faces and a part coacting with said cam faces, said double acting cam means located between and cooperating with said transverse bar and said pressure applying means, all constructed to release the pressure between said wringer rolls by movement of either of said release levers toward or from said frame.

16. In a wringer having a frame having feeding openings for access to the wringer rolls at the respective sides thereof, pressure applying means for said wringer rolls, the combination of transverse bars transverse to the frame and movable in opposite directions in the frame at the respective ends thereof, release levers at the respective sides of said frame having fulcrums on said frame and extending along the top and ends of said respective feeding openings and articulated with said transverse bars for operating the same, double acting cam means operatively located between one of said transverse bars and said pressure applying means, all constructed to release the pressure between said wringer rolls by movement of either of said release levers toward or from said frame, and oppositely operative spring means between and operatively connected with said frame and the other of said transverse bars to move said other of said transverse bars in opposite directions into neutral position for automatically returning said transverse bars and levers to normal positions.

17. In a wringer having a frame having feeding openings for access to the wringer rolls at

the respective sides thereof, pressure applying means for said wringer rolls, the combination of transverse bars transverse to the frame and movable in opposite directions in the frame, release levers at both sides of said frame having fulcrums on said frame and extending along the top and ends of said respective feeding openings and articulated with said transverse bars for operating the same, double acting cam means having slanting cam faces and a coacting part therefor, said double acting cam means located between one of said transverse bars and said pressure applying means, all constructed to release the pressure between said wringer rolls by movement of either of said release levers toward or from said frame, and double acting spring means between and having operative connections with the other of said transverse bars and the frame for automatically returning said transverse bars and said release levers to normal positions.

18. In a wringer having a frame having feeding openings for access to the wringer rolls at the opposite sides thereof, pressure applying means for said wringer rolls, the combination of transverse bars transverse to the frame and movable in opposite directions in said frame, release levers at the opposite sides of said frame extending along the top and ends of said feeding openings and articulated with said transverse bars for operating the same, brackets extending from the opposite sides of the frame at both ends of said feeding openings, said levers pivoted to said brackets at the opposite sides of the frame, and double acting cam means having slanting cam faces and a coacting part therefor, said double acting cam means located between one of said transverse bars and said pressure applying means, all constructed to release the pressure between said wringer rolls by movement of either of said release levers toward or from said frame, and double acting spring means between and having operative connections with the other of said transverse bars and the frame for returning said bars and levers to normal positions.

19. In a wringer having a frame having feeding openings for access to the wringer rolls at the opposite sides thereof, pressure applying means for said wringer rolls, the combination of transverse bars transverse to the frame and movable in opposite directions in said frame at the ends of said feeding openings, brackets extending from the opposite sides of the frame at both ends of said feeding openings, release levers at the opposite sides of said frame extending along the top and ends of said feeding openings and articulated with said transverse bars for operating the same, said levers pivoted to said brackets at the opposite sides of the frame, and double acting cam means having slanting cam faces and a coacting part therefor, said double acting cam means located between one of said transverse bars and said pressure applying means, and all constructed to release the pressure between said wringer rolls by movement of either of said release levers toward or from said frame, and double-acting spring means between and having operative connection with the other of said transverse bars and said frame for returning said bars and levers to normal positions.

20. In a wringer having a frame having feeding openings for access to the wringer rolls at the opposite sides thereof, pressure applying means for said wringer rolls, the combination of transverse bars transverse to the frame and movable in opposite directions in the ends of the

frame, brackets at the ends of the frame at each side thereof above said transverse bars, release levers at both sides of said frame having upper portions extending along the top and downwardly extending end portions extending along the ends of said feeding openings and provided with inward bends toward said frame near the lower ends thereof, said downwardly extending portions pivoted in said brackets at said bends, the lower ends of said downwardly extending portions articulated with said transverse bars for operating the same, double acting cam means having slanting cam faces and a coacting part therefor, said double acting cam means located between one of said transverse bars and said pressure applying means, and all constructed to release the pressure between said wringer rolls by movement of either of said release levers toward or from said frame, and spring means between and having operative connections with the other of said transverse bars and the frame for returning said transverse bars and said levers to normal positions.

21. In a wringer having a frame, wringer rolls journaled therein, a longitudinal bar, and pressure means including connecting means between said frame and said longitudinal bar resisting pressure between said wringer rolls, the combination of pressure relieving means for said connecting means comprising a movable cross-bar movable crosswise of said frame and a coacting part therefor respectively having thereon oppositely slanting cam surfaces and a coacting contact face, said pressure relieving means being located between said frame and said connecting means, and an operating lever having portions at the top and ends of the wringer rolls, said lever pivoted to said frame for movements toward and from said frame and having connection with said cross-bar for moving said cross-bar to relieve said connecting means by each of opposite movements of said operating lever.

22. In a wringer having a frame comprising opposed frame sections, wringer rolls between said frame sections, and pressure means including connecting means between said frame sections resisting pressure between said wringer rolls; the combination of a latch to hold said connecting means in connecting relation, a release bar at the side of said frame, a movable cross-bar movable crosswise of said frame at each end of said frame, said cross-bars respectively having connections with said release bar for being moved thereby, one of said cross-bars and said latch having between them oppositely presented cam surfaces and a coacting contact face therefor, and oppositely acting spring means operatively located between said frame and the other of said cross-bars for normally holding said cam surfaces and said coacting contact face in neutral relation.

23. In a wringer having opposed wringer members, wringer rolls therebetween, and pressure means between said members and said wringer rolls to produce pressure between said wringer rolls, the combination of interpivoted links pivoted to said respective members in manner to be movable to and fro, means wherewith to move the pivot between said links toward the plane in which the pivots between said links and said members are located and to hold said links in such moved position, and a safety release lever pivoted to one of said members and having upper and end stretches about said wringer rolls, said safety release lever having operative con-

nction with said interpivoted links to control movement of said links to move the pivot between said links away from the plane in which the pivots between said links and said members are located.

24. In a wringer having opposed wringer members, one of which is movable lengthwise with relation to the other, wringer rolls therebetween, and pressure means between said members and said wringer rolls to produce wringing pressure between said wringer rolls, the combination of releasable connecting means between said members at one of their ends, interpivoted links pivoted to the other end of said members, the pivot between said links movable toward the plane in which the pivots between said links and said members are located for producing wringing pressure between said wringer rolls, and safety release means for releasing said links for release movement thereof by said pressure, said links reacting on said releasable connecting means for release of said releasable connecting means.

25. In a wringer having a lower member, an upper member, wringer rolls between said members, and pressure means for exerting pressure on said wringer rolls, the combination of interpivoted links pivoted to one end of said members, releasable connecting means between the other end of said members, one of said links being longer than the other at one side of its interpivoting pivot and extended as a lever at the other side of its interpivoting pivot wherewith to move the interpivoted ends of said links toward the plane in which the pivots between said links and said respective members are located for building up pressure in said pressure means, means whereby to hold said links in such moved relation, and safety release means having operative connection with said holding means for movement of said interpivoting pivot away from said plane and for release of said releasable connecting means for release of said pressure on both ends of said wringer rolls.

26. In a wringer having a wringer roll supporting frame, wringer rolls mounted in said frame, said frame comprising opposed frame members between which said wringer rolls are located, the combination of means including a toggle between said frame members for producing pressure between said rolls, said toggle comprising a longer outer link provided with an inner pocket and pivoted to one of said frame members for movement in the direction of the roll axes toward and away from the end of the frame and a shorter inner link pivoted to said longer link and to the other of said frame members in position to be received in said pocket upon approach to parallelism between said links for producing such pressure between said rolls, the edges of the pocket presented to the end of the frame in the pressure position and forming with the frame an enclosure for the shorter link.

27. In a wringer having a wringer roll supporting frame, wringer rolls mounted in said frame, and roll pressure means, said frame comprising opposed frame members between which said wringer rolls are located, the combination of means including a toggle between said frame members for producing pressure between said rolls, said toggle comprising a longer outer link provided with an inner pocket and pivoted to one of said frame members and a shorter inner link pivoted to said longer outer link and to the other of said frame members in position to be received in said pocket upon approach to parallelism be-

tween said links for producing such pressure between said rolls, a latch to hold said frame members in pressure relation, and safety releasing means for said latch.

5 28. In a wringer having a wringer roll supporting frame, wringer rolls mounted in said frame, said frame comprising opposed frame members between which said wringer rolls are located, the combination of connecting means between the respective ends of said frame members to maintain said rolls in normally parallel relation and for producing wringing pressure between said rolls and for release of such pressure and including a releasable connection between 10 said frame members at one of their ends and a toggle comprising links pivoted to one another and to the other of the ends of said frame members and movable in the plane of said rolls, said connecting means having parts constructed to react one upon the other for producing such wringing pressure between said rolls and for release of said pressure, and means for release of one of said connecting means to induce release in the other of said connecting means.

29. In a wringer having a wringer roll supporting frame, wringer rolls mounted in said frame, said frame comprising opposed frame members between which said wringer rolls are located, a pivotal connection between said frame members at one of their ends, the combination of a toggle between said frame members at the other of their ends to maintain said rolls in normally parallel relation and for producing pressure between said rolls, said toggle comprising an outer link provided with an inner pocket and pivoted to one of said frame members and an inner link pivoted to said outer link and to the other of said frame members, said outer link extended as a manual operating part beyond the pivot between said links, and said links movable toward said frame members for producing such pressure between said rolls, with said inner link located in said pocket and between said outer link and said frame members and the edges of the pocket presented to and forming with the frame an enclosure for the inner link.

30. In a wringer having a frame, rolls mounted in the frame, a removable top bar on the frame, and pressure means between the top bar and the rolls, the combination of means for detachably securing one end of the bar to the frame, securing means between the other end of the bar and the frame comprising a toggle with one link pivoted to the frame, the other link pivoted to the bar and to said first link, and having an extension forming a handle for manipulating said toggle, the construction being such that the pivots of said links may be brought close to but short of a straight line position, whereby pressure between the bar and the frame will bias said toggle into a released position, and latching connections between said frame and said extension to secure said toggle in a pressure retaining position.

31. In a wringer having a wringer roll supporting frame, wringer rolls mounted in said frame, one of said wringer rolls being slidably mounted, said frame comprising opposed frame members between which said wringer rolls are located, the combination of a toggle between said frame members for producing wringing pressure between said rolls, said toggle comprising a link provided with an inner pocket and pivoted to one of said frame members and an inner link pivoted to said pocketed link and to the other of said frame members in position to be received in said pocket upon

approach to parallelism between said links for producing such pressure between said rolls, the edges of the pocket abutting and forming with the frame an enclosure for the shorter link.

32. In a wringer having a wringer roll supporting frame, wringer rolls mounted in said frame, one of said wringer rolls being slidably mounted, said frame comprising opposed frame members between which said wringer rolls are located, the combination of a toggle between said frame members for producing wringing pressure between said rolls, said toggle comprising a longer outer link provided with an inner pocket and pivoted to one of said frame members and a shorter inner link pivoted to said longer link and to the other of said frame members in position to be received in said pocket upon approach to parallelism between said links for producing such pressure between said rolls, the edges of the pocket abutting and forming with the frame an enclosure for the shorter link.

33. In a wringer having a roll supporting means, rolls therein, said means comprising a lower frame, a releasable top frame, and pressure means for the rolls; the combination of a mechanism comprising a toggle, one link being mounted for pivotal movement on the top frame and the other link of the toggle being pivoted to the first-mentioned link and to the lower frame, said first-mentioned link having an arm extending past the pivots of the second-mentioned link and forming a lever for actuating the toggle to position the same to exert pressure on the pressure means.

34. In a roll wringer releasing device for a wringer having a lower wringer frame, a releasable top frame therefor, wringer rolls disposed in the lower frame, tensioning means for the rolls supported in the upper frame, the same being capable of moving the upper frame relative to the lower frame to relax pressure between the rolls, the combination of a toggle link mechanism connecting the upper and lower frames the same being operable by the upper frame when the latter is moved by said tensioning means, latch mechanism cooperative with said link mechanism adapted to prevent operation of the latter by the described movement of the upper frame whereby said movement is prevented and pressure between the rolls is maintained and manual means for moving said latch to permit operation of the toggle link mechanism to allow movement of the upper frame whereby pressure between the rolls is relaxed.

35. In a wringer having a frame having upright portions, wringer rolls supported by the upright portions of said frame, a separable cross head member supported by said upright portions, adjustable spring means carried by said cross head member for normally holding said wringer rolls in pressure contact, the combination of toggle link mechanism having inseparable members for retaining said cross head member in normal working position and joining the cross head to at least one of the upright portions, a movable latch member for holding the toggle mechanism in operable relation when retained in holding position and so that the pressure load is divided between the toggle mechanism and latch, said spring means being operable to move the toggle mechanism when the latch is not retained in holding position whereby the pressure between the rolls is released.

36. In a wringer having a frame, rolls mounted in the frame, a removable top bar on the frame,

5 pressure means between the top bar and the rolls, and means for detachably securing one end of the bar to the frame, the combination of securing means between the other end of the bar and the frame comprising a toggle with one link pivoted to the frame, the other link pivoted to the bar and to said first link, the construction being such that the pivots of said links may be brought close to but short of a straight line position, whereby pressure between the bar and the frame will bias said toggle into a released position, and latching means to secure said toggle in a pressure retaining position.

42. A roll wringer mechanism for a wringer having a frame comprising lower and top frames, wringer rolls in the frame, and pressure means for the rolls, a mechanism capable of operating said pressure means comprising a lever link on one end of the top frame and mounted for pivotal movement thereon, said lever link having portions included in a non-locking toggle mechanism adapted by movement of said lever link to bring about operation of said pressure means to press the rolls together, and a lock and release mechanism coacting with said toggle whereby the top frame is held in or released from pressure position.

43. A roll wringer mechanism for a wringer having a frame comprising lower and top frames, wringer rolls in the frame, and pressure means for the rolls, a mechanism operating the pressure means to render the same capable of pressing the rolls together comprising a lever link on one end of the top and mounted for pivotal movement thereon, the same having portions included in a non-locking toggle mechanism adapted by movement of said link to operate said pressure means, means for holding the link in pressure applying position, and means associated with the link for disabling said holding means.

44. A roll wringer mechanism for a wringer having a frame comprising lower and top frames, wringer rolls in the frame, and pressure means for the rolls, a mechanism operating the pressure means to render the same capable of pressing the rolls together comprising a lever link mounted for pivotal movement at one end of the top frame, the same having portions included in a toggle mechanism adapted by movement of said lever link to operate said pressure means, means for holding the lever link in pressure applying position, and mechanism associated with the lever link and movable independently thereof to disable said holding means.

45. A device of the class described having a frame comprising a lower frame and a top frame movable toward or away from the lower frame, wringer rolls in the frame, and pressure means for the rolls made active by movement of the top frame toward the lower frame, the combination of mechanism capable of moving the top frame comprising a lever link extending from one end of the top frame and mounted for pivotal movement thereon, said lever link having portions included in an unstable toggle mechanism adapted by movement of said lever link to bring about movement of the top frame to render said pressure means active to press the rolls together and means for releasably securing said toggle mechanism with said pressure means active.

46. In a wringer release mechanism for a wringer having spaced side frame members and between which the wringer rolls may extend, means for imposing wringing pressure upon the wringer rolls, and means for effecting a quick release of the pressure exerted by said pressure means, the combination of means for operating said pressure releasing means comprising, a bar extending longitudinally of the wringer between said side frame members, a pivot connection between one end of said bar and one of said side frame members, means providing a sliding connection between the other end of said bar and

the other of said side frame members, and means engageable by said connection means upon movement of said bar with respect to said pivot for operating said pressure releasing means.

47. In a wringer having spaced side frame members, upper and lower rolls journaled in said side frame members, a releasable top frame member associated with said side frame members and a spring carried and normally tensioned between said top frame member and the rolls, the combination of toggle means normally securing said top frame member in spring tensioning position, a bar carried by said side frame members, means mounting said bar for shifting movement transversely of one of the frame members, and means engaged with said toggle means and associated with said bar for releasing said toggle when said bar is shifted.

48. In a wringer having a frame having upright portions, wringer rolls supported by the upright portions of said frame, a separable cross head frame portion supported by said upright portions, and spring means reacting between said frame and said rolls for normally holding said wringer rolls in pressure contact, the combination of toggle link mechanism having members for retaining said cross head in normal working position and joining the cross head to at least one of the upright portions, a movable latch member for holding the toggle mechanism in operable relation when retained in holding position and so that the pressure load is divided between the toggle mechanism and latch, said spring means being operable to move the toggle mechanism when the latch is not retained in holding position whereby the pressure between the rolls is released.

49. In a wringer mechanism, in combination, wringer rolls, roll pressure members acting on opposite sides of the roll axes for pressing the rolls together, pressure sustaining means connecting said members including toggled links connected to the respective members and a pressure sustaining hook movable from its pressure sustaining position, and safety release means for moving the hook from its pressure sustaining position.

50. In a clothes wringer, separable roll pressure applying members, means for maintaining said members in pressure applying relation including unstable toggle links pivoted respectively to the pressure applying members and each other and forming in pressure maintaining position an acute angle at the common pivot, a latch for maintaining the toggle links in pressure maintaining position, and safety release means for moving the latch from the pressure maintaining position.

51. In a clothes wringer, separable roll pressure applying members, means for maintaining said members in pressure applying relation including unstable toggle links pivoted respectively to the pressure applying members and each other and forming in pressure maintaining position an acute angle at the common pivot, a latch on one of said members for holding the toggle links in the pressure maintaining position, and means for moving the latch from its pressure maintaining position.

GUSTAVE H. JANTZ.
